UNITED STATES PATENT OFFICE

JOHN A. MACREADY, OF DAYTON, OHIO, ASSIGNOR TO FRIGIDAIRE CORPORATION, OF DAYTON, OHIO, A CORPORATION OF DELAWARE

DESIGN FOR A DRINKING-WATER COOLER FOUNTAIN

Application filed November 30, 1928. Serial No. 29,074. Term of patent 14 years.

To all whom it may concern:

Be it known that I, JOHN A. MACREADY, a citizen of the United States of America, residing at Dayton, county of Montgomery, State of Ohio, have invented a new, original, and ornamental Design for Drinking-Water Cooler Fountains, of which the following is a specification, reference being had to the accompanying drawing, forming part thereof.

The figure is a view in perspective of a drinking water cooler fountain.

I claim:

The ornamental design for a drinking water cooler fountain as shown.

In testimony whereof I hereto affix my signature.

JOHN A. MACREADY.
